TWIRLER RING FOR TYPEWRITER PLATENS

Charles J. Watson, Brooklyn, N. Y., assignor to Peerless Key Company, Inc., New York, N. Y., a corporation of New York

Application May 9, 1936, Serial No. 78,762

5 Claims. (Cl. 74—558)

This invention relates to improvements in twirler rings for use on typewriter platens.

It has been found desirable to facilitate the rotation of platens for typewriters to provide the 5 knobs of the platens with twirler rings generally made of rubber or a similar material. Heretofore, twirler rings have been objectionable in that they gripped the knobs of the platen so tightly that the rings were hard to the touch.

10 It is an object of this invention to provide a twirler ring which can firmly grip the knob of a typewriter platen and at the same time have a "cushioning" effect which is easy upon the fingers of an operator.

15 A further object is the provision of a twirler ring for typewriters having an internal circumferential groove centrally positioned so as to produce a cushioning effect, without impairing the grip of the ring on the knob of a typewriter.

20 These and other advantageous objects which will later appear, are accomplished by the simple and practical construction and arrangement of parts hereinafter described and exhibited in the accompanying drawing, forming part hereof, and 25 in which:

Fig. 1 is a side view, of a knob for typewriter platens having fixed thereon a twirler ring embodying my invention.

Fig. 2 is an elevational view partly in section 30 of a portion of a platen and knob therefor, having mounted thereon twirler ring in accordance with my invention.

Fig. 3 is a sectional view of a portion of the 35 twirler ring showing the manner in which the cushioning effect is produced, and

Fig. 4 is a sectional view of a modified form of the invention.

Referring to the drawing, there is shown a platen 4 mounted on a shaft 5 having a circular 40 knob 6 which is knurled as is customary in typewriters. Mounted on the knob 6 is a twirler ring which comprises an annulus 7 made of rubber or similar material and having the outer periphery thereof knurled and the inside of the twirler ring 45 being also preferably knurled to grip the knurled surface of the knob 6. The annulus 7 has a flange 8 on the outer side of the knob 6 and a shorter flange 9 on the inner side of the knob.

In order to produce a cushioning effect, the 50 annulus 7 is provided on the inner surface thereof with a centrally positioned circumferential groove 10 which is bordered on each side by the knurled portions 11 and 12 which firmly grip the knob 6 as above described.

55 As shown in Fig. 3, when the twirler ring 7 and the knob 6 are gripped, due to the groove 10 a

cushioning effect is produced which is more pleasant to the touch than has heretofore been the case with twirler rings of the type described.

In Fig. 4 is shown a modified form of the invention in which the annulus is provided with a 5 centrally positioned circumferential groove 20 and has a plurality of spaced ribs 21 projecting into the groove. The ribs 21 contact the knob 6 and provide sufficient support for the collapsing 10 of the twirler ring.

The foregoing disclosure is to be regarded as descriptive and illustrative only, and not as restrictive or limitative of the invention, of which obviously an embodiment may be constructed including many modifications, without departing 15 from the general scope herein indicated and denoted in the appended claims.

Having thus described my invention, what I 20 claim as new and desire to secure by Letters Patent, is:

1. A twirler ring for knobs of typewriter platens, comprising an annulus having on the inner surface thereof a centrally positioned circumferential groove, and a plurality of spaced ribs projecting into the groove. 25

2. A twirler ring for knobs of typewriter platens, comprising an annulus having on the inner surface thereof a centrally positioned circumferential groove, the surface of the annulus bordering the groove being knurled to enable it to 30 firmly grip a platen knob.

3. A twirler ring for knobs of typewriter platens, comprising an annulus having on the inner surface thereof a centrally positioned circumferential groove, a plurality of spaced ribs projecting into the groove, and having an inner and outer flange of different dimensions. 35

4. A twirler ring for knobs of typewriter platens, comprising an annulus having on the inner surface thereof a centrally positioned circumferential groove with parallel side walls, the inner surface of the annulus bordering the groove being knurled to enable it to firmly grip a platen knob. 40

5. A twirler ring for knobs of typewriter platens, comprising an annulus having on the inner surface thereof a centrally positioned circumferential groove with parallel side walls, the inner surface of the annulus bordering the groove being knurled to enable it to firmly grip a platen 50 knob, and a plurality of spaced ribs projecting from the bottom of the groove to engage a platen to provide sufficient support to prevent collapsing of the twirler ring.

CHARLES J. WATSON. 55
